UNITED STATES PATENT OFFICE.

MARGARET BRIDGMAN, OF CANADENSIS, PENNSYLVANIA.

DESIGN FOR A HANDKERCHIEF OR THE LIKE.

Application filed May 3, 1927. Serial No. 21,833. Term of patent 7 years.

To all whom it may concern:

Be it known that I, MARGARET BRIDGMAN, a citizen of the United States of America and a resident of the village of Canadensis, county of Monroe, and State of Pennsylvania, have invented a new, original, and ornamental Design for Handkerchiefs or the like, of which the following is a specification, reference being had to the accompanying drawing, forming part thereof.

The design comprises a combination of the planet symbol and the sign of the zodiac for the month of September.

The figure is a plan view of a handkerchief, showing my new design.

I claim:

The ornamental design for a handkerchief or the like substantially as shown and described.

MARGARET BRIDGMAN.
